UNITED STATES PATENT OFFICE

2,251,795

GAS GENERATING METHOD

Harold E. Howard, Bridgman, Mich., assignor to
 National Gas Service, Incorporated, Benton
 Harbor, Mich., a corporation of Michigan

Application April 19, 1935, Serial No. 17,191

8 Claims. (Cl. 43—213)

My invention relates to a gas generating apparatus.

As is well understood by those skilled in this art, there are several different methods of generating gas from a more or less volatile material and one of these is disclosed in the patent to Curme, Jr., et al. No. 1,638,434, patented August 9, 1927. In this disclosure the patentee utilizes at least two combustible materials of differing volatility stored in separate vessels, one of said materials having different characteristics from the other one.

Some of the disadvantages of this system lie in the requirement that two receptacles are necessary. Also two distinct and different volatile gases are necessary. These gases have different characteristics and different B. t. u. content and obviously frequent adjustments of the different media would be necessary and involve more or less trouble.

My system is much improved over the one just described inasmuch as it is not only more simple but is more efficient and is cheaper to operate and will operate under more variable conditions but yet will produce a vapor of stable specific volume and of uniform heating value.

Also, my system does not require the application of any heat thereto inasmuch as I utilize the heat from the earth. Also, I utilize butane as my combustible material and my arrangement is such that a 180 gallon tank, buried several feet below the earth's surface, is sufficient for use for one year under ordinary conditions for a single family.

Another feature of my invention resides in the manner in which I transfer the butane from the tank wagon to the underground tank with a minimum amount of labor and expense and also there is practically no fire hazard during this transfer. Thus the system is practical from all angles and produces a gas of stable characteristics at a very reasonable cost.

Another advantage is my method of utilizing a vacuum pump for aiding in the transfer of the liquid. Also, this same pump may be used, due to its novel attachments, as a means for transferring a quantity of gas above the liquid in the tank which is being filled. This serves two purposes. In the first place it starts the customer or consumer off with a full tank of gas and secondly, it prevents waste of the gas.

It is to be appreciated that the inflammable liquid might not only include butane but also pentane, hexane, and other higher paraffins, together with any olefin, aromatic alicyclic or other

compound of suitable volatility, or ethane, propane, ethylene or other high volatile materials, or any chemical compound of like nature.

Other advantages and features will become apparent during the following description.

In the drawings—

Fig. 1 is a sectional view through my system showing the same in operation, the supply tank also being shown just after filling has been completed.

Fig. 2 is a view illustrating a modification of my invention.

Fig. 3 is a more or less schematic view of the preferred form of my filling system.

Like reference characters refer to like parts throughout the several views.

Numeral 10 indicates a tank of the desired capacity, say 180 gallons, and this tank is located in the earth or ground 11 as shown. For use in Michigan this tank would be buried approximately three feet from the earth's surface in Central Michigan and perhaps five or six feet under the earth's surface in Northern Michigan. Thus the temperature of the tank and its contents would be maintained at a substantially constant temperature averaging perhaps 60° F. although in wintertime this temperature might sometimes drop to 45° F. and in the summer might run as high as 70° F.

The tank 10 has a partition 12 welded or otherwise fastened at 13 completely around the interior of the tank so as to divide the tank into compartments of suitable size. As shown, one of these compartments is considerably larger than the other one. The partition 12 has a small orifice or opening 14 located an inch or so from its bottom. This orifice is always made smaller than the opening 15 which will be referred to later in the specification. In this particular instance, the orifice 14 may be approximately one-eighth inch in diameter. Or, the partition may contain a small opening at or near its bottom, which opening, regardless of its shape or position in the partition, would accomplish the same results as claimed for the arrangement with an orifice as shown at 14. Any sort of an opening at or near the bottom of the tank so that the liquid may pass from one compartment to another compartment may be utilized but the flow is controlled or regulated as desired, by predeterminedly fixing the size of the opening.

The partition 12 has a second opening 15, a short distance from the top of the tank, and a pipe 16 is welded or tightly fitted in this opening and leads downwardly into the smaller com-

partment 17 as clearly shown in Fig. 1. An outlet pipe 18 leads from the smaller compartment 17 and carries the gas or vapor to its point of consumption.

The other compartment is designated by the reference numeral 8 and has two spaced pipes 19 and 20 leading upwardly therefrom and carrying valves 21 and 22, respectively, at their upper ends. These pipes extend downwardly into the compartment 18 below the lowermost point of the opening 15.

Numerical 30 indicates the tank of the supply wagon which carries the butane or the like 40. A valved outlet 31 leads from the bottom of this tank 30 into the hose 32 and into the transparent member 33 carrying the revoluble vane 34. A valve 36 is located below the transparent member 33. This valve 36 receives a union 35 whereby the same may be detachably connected to the valve 22.

Another valved outlet 36' leads into the hose 37 to a transparent member 38, having a revoluble vane 39. A revoluble union member 42 is located below the member 38 and detachably connects the end of this hose onto the pipe 19 as clearly shown.

Referring now to Fig. 2, numeral 50 indicates a tank, buried a predetermined distance, having a partition 51 therein whereby the tank is divided into two compartments. A gas outlet 52 leads from one compartment. Filling pipes 53 lead into the other compartment.

A U-shaped pipe 55 tightly extends through the partition 51 near its top and terminates with one arm 56 near the bottom of the larger compartment and with its other arm or depending portion 57 extending to near the bottom of the other compartment. The portion 57 has a restricted nozzle opening 58.

Referring now to Fig. 3, numeral 10 indicates the tank, buried in the earth 11, and having the outlet pipe 18. Filling pipes 19 and 20 lead upwardly from the tank 10 and are equipped with valves 21 and 22.

The tank wagon 9, carries the tank 30, having a valved outlet 31 near its bottom. A hose 32 connects to the valved outlet 31 and terminates in a transparent gauge 33, valve 36 and union 35.

A second union 42 connects onto the valve 21 and leads upwardly to the transparent member 38 which in turn connects onto the hose 37.

A vacuum pump 60 has an inlet 61 which is branched to form an upwardly extending pipe 62 and a laterally extending pipe 63, the former having a valve 64 and the latter a valve 65. The pipe or hose 37, previously referred to, connects onto the valve 65.

The vacuum pump 60 has an outlet 70 valved at 71 and 72 and leading into the tank 30 at the top thereof. A pipe or connection 73 extends from the portion of the pipe 70 between the valves 71 and 72 downwardly into the valve 64.

A pipe 76, having a valve 77, leads from the outlet pipe 70, below the valve 71, to the hose or passageway 37. Gauges 78 and 79 are located as shown.

The operation

After the tank 10 has been filled with the butane 40, the same gradually comes to the same temperature as the earth surrounding it. The restricted opening permits a leveling of the liquid. When this occurs the vapor pressure becomes constant throughout the entire system including the chambers or compartments 17 and 8. The 75

space above the butane 40, in both compartments, is filled with inflammable gas under exactly the same pressure.

When the gas is burned at its point of use, the gas will flow through the outlet pipe 18 and consequently the pressure within the compartment 17 will be reduced. If the use of the gas is slow the butane will simply vaporize sufficiently to maintain the vapor pressure in the compartment 17 constant. However, if the gas is used more rapidly, as is ordinarily the case, then the reduction of pressure within the compartment 17 will cause the pressure within the compartment 8 to push the gas therewith through the agitating tube 16. This will cause the same to bubble upwardly through the butane in the compartment 17 and agitate it and generate additional gas. The greater the use of gas the greater its flow through the outlet pipe 18 will be and consequently the reduction of pressure in the chamber 17 will be increased. This will cause even more of the gas to flow from 8 through the pipe 16 and bubble upwardly to increase the agitation and thus automatically generate a larger supply of gas. Thus, the greater the demand for gas, the greater the agitation and consequently the greater the generation of the gas. As will be readily apparent, gas will be required in varying amounts at different times. For example, prior to the evening meal, the maximum demand is usually present. Thus, the demand for gas is varying and fluctuating.

The opening 14 is a restricted opening and this prevents any rapid flow of butane therethrough. Of course, some butane will flow through this opening under the variable gas pressures but there will not be sufficient flow to interfere with the operation set forth above. Furthermore, this flow of the butane through the orifice 14 or other suitable opening will cause additional agitation which will likewise advantageously function to produce additional gas.

With reference to Fig. 2, the decrease in the smaller compartment due to the out flow of gas through the outlet pipe 52, will cause a differential in pressure to result whereby the liquid will flow upwardly through the arm 56 and then around the top of this pipe and downwardly through the arm 57 and out of the restricted member or nozzle 58 thus giving agitation and additional gas. The greater the differential, the greater the agitation as is desirable and necessary and as is obtained by my construction.

The filling, necessary every year or so, is accomplished by a truck carrying the tank 30. The several conduits are connected together as shown in Fig. 1, all of the valves being closed.

The first step is to open the valves 36 and 21 whereby the gas pressure in the tank wagon 30 and the gas pressure in the underground tank will be equalized. Next the valves 31, 36 and 22 are opened and the liquid gravitates from the tank 30 to the underground tank 10. This flow continues until the bottom of the pipe 12, leading upwardly to the hose 37, is covered by the liquid and, when this occurs, the flow continues for a short time until the gas pressure in the tank 10 builds up and causes the liquid to rise upwardly through the transparent member 33 to cause the revoluble vane 39 to revolve. When this occurs, the operator understands that the filling is finished and disconnects the unions 35 and 42 from the valve 22 and 21 previously having closed the several valves. If the operator

does not notice the revolving of the vane 39, no harm is done because the flow of liquid automatically ceases inasmuch as the pressure within the hose 37 is balanced by rising to the same height as the butane within the tank 30.

Although the filling pipes 19 and 20 are shown as extending into the tank 10 the same distance, it is to be understood that it is only the extension of the outlet pipe 19, which is connected to the hose 37, which controls the automatic cessation of the flow of the liquid. Also, it is to be understood that the butane 40 flows through the orifice 14 during the filling operation and thus the entire tank is filled to the desired level. The novel manner of extending the pipe 19 into the tank and the system or method utilized is necessary as space must be left above the liquid for a certain quantity of gas to gather and to be stored. Approximately thirty gallons of space should be left in a one hundred eighty gallon tank above the liquid level.

Referring now to Fig. 3, the vacuum pump 60 may be operated in order to reduce the pressure within the underground tank. The valves 64 and 77 should be closed and the valves 65, 71 and 72 should be open. This draws the gas or vapor upwardly through the hose 37, the valve 21 having been opened, and then through the valve 65 and forces the gas upwardly through the direct connection 70 to the space above the butane 40. Thus the pressure is decreased in the tank which is to be filled and increased in the tank which is to be emptied, this manner of operation giving a double effect and increasing the speed thereof.

If desired, the valves 31, 36 and 22 may remain closed until the vacuum within the tank 10 is reduced to a desired amount and then opened, the vacuum pump 60 having ceased its operation, and this is desirable inasmuch as it permits the operator of the truck to more expediently leave the filling manipulation unattended as he inspects the stoves, lamps, and the like which are utilized in the manufactured gas.

When this is done, the flow of the butane will cease automatically because the lower end of the pipe 20 will be covered with the liquid and after a further rise the pressure will build up within the tank 10 until it balances the pressure head of the butane and its vapor pressure thereabove. The next step is the opening of the valves 64 and 77 and the closing of the valves 65 and 71. Upon operation of the vacuum pump 60, the gas or vapor of the butane will be drawn through a portion of the pipe 70, then downwardly through the open valve 64 and into the vacuum pump 60. The vacuum pump 60 will discharge the gas upwardly through a short portion of the pipe 70 and then laterally through the pipe 76, then through the valve 77 and next downwardly through the hose 37 and its attachments, into the underground tank 10. Thus the customer or consumer is assured of a full and complete measure of gas after the refilling operation and furthermore the vapors which would otherwise remain in the tank wagon are not lost. Thus a material percentage of the butane is saved by this novel system.

The full line arrows shown on the drawings indicate the path of the gas from the underground tank while the dotted arrows indicate the path of the gas to the underground tank.

The invention is defined in the appended claims and is to be considered comprehensive of all forms of structure coming within their scope.

I claim:

1. The method of producing gas which consists in providing liquid butane or the like in two separate chambers to only a predetermined depth or less whereby spaces of certain minimum size are respectively formed above the surfaces of the liquid, withdrawing the gas to be used from one of said spaces, at a predetermined rate, providing a flow of liquid between the chambers near their bottoms, providing a flow of gas from the other of said spaces to a point below the surface of the liquid in the chamber below the space from which the gas to be used is withdrawn, said flows of liquid and gas having a predetermined relationship such that the withdrawal of gas from said one of said spaces will diminish its pressure sufficiently to cause the gas pressure in the other space to overbalance the controlled gradually increasing liquid pressure in the chamber below the space from which the gas to be used is withdrawn whereby the said flow of gas between the chambers will occur.
2. The method of producing gas from an inflammable homogeneous liquid hydrocarbon which consists in locating the same in two separate bodies at the same altitude, providing a chamber of predetermined size above each, leading gas from one chamber to its points of use and leading gas with but little pressure drop from the other chamber to a point within the liquid hydrocarbon in the place below the chamber from which the gas flows to its points of use and causing a slow rate of flow between the two chambers.
3. The method of producing gas from a hydrocarbon liquid such as butane which consists of placing a quantity of the same liquid in each of two adjacent chambers located substantially in the same level, one of said chambers being a gas supply chamber and the other being a fuel reserve chamber, closing said fuel reserve chamber to the exterior, flowing gas from said gas supply chamber, conducting gas formed in said fuel reserve chamber into said gas supply chamber below the level of liquid therein and conducting liquid from said fuel reserve chamber into said gas supply chamber at a considerably lesser rate of flow than the gas outlet from the gas supply chamber.
4. The method of producing gas from a hydrocarbon liquid such as butane which consists of placing a quantity of the same liquid in each of two chambers, one of said chambers being a gas supply chamber and the other being a fuel reserve chamber, closing said fuel reserve chamber to the exterior, flowing gas from said gas supply chamber to reduce the pressure therein, conducting gas from said fuel reserve chamber into said gas supply chamber below the level of liquid therein and overcoming the hydrostatic pressure thus encountered by means of differences in pressure resulting from said flowing gas from said gas supply chamber and conducting liquid from said fuel reserve chamber into the said gas supply chamber at a considerably lesser rate of flow than the gas outlet from said gas supply chamber.
5. The method of producing gas from a hydrocarbon liquid such as butane which consists of placing a quantity of the same liquid in each of two chambers, one of said chambers being a gas supply chamber and the other being a fuel reserve chamber, closing said fuel reserve chamber to the exterior, flowing gas from said gas supply chamber to reduce the pressure therein, conducting gas from said fuel reserve chamber into said gas supply chamber below the level of

liquid therein and overcoming the hydrostatic pressure thus encountered by means of differences in pressure resulting from said flowing gas from said gas supply chamber and conducting liquid from said fuel reserve chamber into said gas supply chamber at a considerable lesser rate of flow than the gas outlet from said gas supply chamber or vice versa, the flow of said liquid between said chambers being governed by differences in pressure between said chambers.

6. The method of producing combustible gas from a normally gaseous liquefied combustible which comprises maintaining out of communication with the atmosphere a supply of said liquefied combustible in two bodies having normally a common level with vapor spaces thereabove and in separate but communicating chambers, withdrawing vapor of the combustible to a point of use from the vapor space of one chamber, simultaneously causing thereby vapor from the vapor space of the other chamber to be delivered through a conduit therefrom to a point below the surface and within the liquefied combustible in the first-mentioned chamber, and causing the liquefied combustible in the second chamber to exert a pressure and level equalizing effect on the liquefied combustible in the first chamber by flow through a restricted communication therebetween.

7. The method of producing combustible gas 30

from a normally gaseous liquefied combustible which comprises maintaining out of communication with the atmosphere a supply of said liquefied combustible in two bodies having vapor spaces thereabove and in separate but communicating chambers, withdrawing vapor of the combustible to a point of use from the vapor space of one chamber, simultaneously causing thereby vapor from the vapor space of the other chamber 10 to be delivered through a conduit therefrom to a point below the surface and within the liquefied combustible in the first-mentioned chamber, and causing the liquefied combustible in the second chamber to exert a pressure and level 15 equalizing effect on the liquefied combustible in the first chamber by flow through a restricted communication therebetween.

8. The process of generating gas from a volatile liquid hydrocarbon which comprises enclosing the same in two chambers, withdrawing the gas to be used from the upper part of the first chamber, passing the gas from the upper part of the second chamber into the first chamber below the level of the liquid hydrocarbon therein when the pressure in the first chamber is lower than the pressure in the second chamber and providing a limited flow of liquid between the two chambers to gradually equalize their respective pressures and liquid levels.

HAROLD E. HOWARD.
